FILM DRIER

Rudolph Simmon, Long Island City, N. Y.

Application February 7, 1938, Serial No. 189,123

1 Claim. (Cl. 34—26)

The present invention is directed to photographic films, and more particularly to an apparatus for drying the same after such films are developed.

Apparatus for drying films has been known for a considerable number of years and has been used. Various types of apparatus for such use have been proposed. Among such apparatus is a type wherein there was provided a boxlike structure having within the same a motor-driven pump and having in a separate compartment a series of incandescent lamps. Air from the pump or blower was caused to flow over the lamps to take up heat therein, and the warmed air was then caused to pass into and through another boxlike structure containing photographic plates to be dried. These plates were held in suitable recesses in the bottom of the box and the air was intended to pass thereover and to dry the same by direct contact with said plates.

Such an apparatus was inefficient in that a series of lamps were used for heating the air, resulting in an ineffective transfer of heat and causing a needless expenditure of energy. The drying compartment was very large compared to the photographic plates therein so that a large amount of air was wasted, again causing a needless expenditure of energy in circulating the air. Because of the manner of positioning the photographic plates, the drying was not uniform, resulting many times in defective plates.

Another type of apparatus previously used consisted in the provision of suitable chambers and an endless chain arrangement with numerous pulleys, sprockets, driving devices and the like. There was also provided heating means for raising the temperature of the drying chambers to the proper degree. The film in relatively long lengths was intended to pass substantially continuously through the apparatus and to be thus progressively dried. However, such an apparatus was quite complicated, expensive to build, and required expert operators in order that it might function satisfactorily. The arrangement was such that it could not be adapted for the drying of short lengths of film such as are commonly used in ordinary photographic work.

The present invention is intended to overcome the difficulties and disadvantages of prior art structures, it being among the objects thereof to provide a drying device for photographic films which shall be simple in construction and efficient in operation.

It is a further object of the present invention to provide a film-drying apparatus which is

small, compact, easily set up, and capable of manipulation without expert operators.

It is a still further object of the present invention to provide an apparatus of the character described in which the wet film may be readily and conveniently introduced into the apparatus without danger of the wet emulsion being injured.

In practicing the present invention I provide a vertically placed elongated tube of relatively narrow cross section. Preferably, the tube is circular and the film to be dried is hung in said tube from the top thereof. The diameter of the tube is proportioned to the width of the film in such a manner that the film practically fills the space within the tube. However, the film is kept in a vertical position so that there is no danger of contacting of the film with the sides of the tube, thereby eliminating the possibility of damage or injury to the emulsion thereon.

Said tube is placed upon a base consisting of an enclosure in the bottom of which is a motor-driven fan or blower and in the upper portion of which is a heating element. Air from the blower is caused to pass over the heating element and into the bottom of the tube or casing, passing upwardly and outwardly through the tube thereof. The heated air thereby comes into direct contact with the film throughout its entire length, and because of the restricted passageway, the operation is quite efficient and the minimum amount of air for the drying operation is used. Because of a direct connection between the enclosure and the casing, there is a minimum of resistance to the flow of air and thus an increased efficiency of operation. The film is maintained in a vertical position during the drying operation, and for this reason there is no danger of shrinkage or wrinkling of the film by reason of the drying.

Under some conditions it may not be necessary to provide heat for the air used in the drying operation. Therefore there is provided a pair of switches connected to the heating element and motor respectively. Said switches may be operated independently or simultaneously to place either the blower into operation or to utilize both the blower and the heating element.

In the accompanying drawing constituting a part hereof and in which like reference characters indicate like parts;

Fig. 1 is a view in vertical cross section of an apparatus made in accordance with the present invention, some of the elements thereof being shown diagrammatically; and

Fig. 2 is a transverse cross-sectional view of the apparatus taken along the line 2—2 of Fig. 1.

The apparatus described and claimed herein comprises a tube 1 of any suitable material, usually of light metal but obviously may consist of non-metallic materials. Said tube is circular in cross section and is of rather small diameter compared to its length.

The lower end of said tube or casing 1 is provided with a flange 2 which is secured by suitable means to a similar flange 3 formed on the upper end of an enclosure 4. In the bottom of said enclosure is a blower 5 operated by motor 6.

A source of electricity is attached to lead lines 7 which are operatively connected to the motor 6 by suitable wires 9 having a switch 10 interposed in said line. A heating element 11 in the upper part of enclosure 4 has connected thereto wires 12 and 13, also in the circuit 7, and provided with a switch 14 in the line.

The upper end 15 of the casing 1 is open to allow a free flow of air, and a support 16 having film-holding members 17 is secured or placed on the top of casing 1. Support 16 is removably held on the top of tube 1, whereby it may be removed, the film clipped thereto and then replaced. The ends of a strip of film are secured by clips 17, and a roller or other device 20 is inserted at the loop 21 formed in the film when it is hung in a vertical position so that the major portion of the film comprises two parallel portions 18 and 19 held in a vertical position and suspended from the top of casing 1. The emulsion side of the film faces outwardly so that the roller or weight 20 does not injure the same. Said roller insures that the film is held in a vertical position and prevents contacting of the film with the sides of the casing 1.

As will be seen more particularly in Fig. 2, the width of the film is such that the edges thereof almost touch the sides of casing 1. It will further be noted that the emulsion side of the film, although it faces the casing 1, cannot come in contact with it so that there is no danger of the wet emulsion sticking to the casing and thus causing blemishes in the dried film.

In the operation of the device, the member 16 holding the film in vertical position as above described is placed as shown in Fig. 1. Switches 10 and 14 are closed, causing the blower 5 to operate and to cause a flow of air to pass upwardly through the enclosure 4. In passing over the heater 11, the air is warmed to a desirable extent, and the warm air then passes directly into the casing 1, there being no obstructions to the flow of air nor any changes in direction of flow. Thus there is a minimum of resistance to the flow of air. By reason of the positioning of the film and

the presence of roller 20, practically all of the air is caused to flow into the spaces 22 and 23 between the face of the film and the sides of the casing. By thus restricting the passage, the drying effect is highly efficient and the amount of air necessary for the operation is greatly reduced. Thus drying of the film will take place rapidly and effectively with a minimum expenditure of energy.

Under some conditions, particularly when the humidity of the air is quite low and when the temperature of the air is sufficiently high, heating of the stream of air may be dispensed with. In such cases, in the operation of the device, only the switch 10 is closed and switch 14 is allowed to remain open.

Although I have described my invention setting forth a single embodiment thereof, it is apparent that various changes in the details of construction of my device may be made within the spirit of the present invention. For example, if it is desired to have a constant temperature of air at all times, I may introduce into the circuit of heating element 11 a thermostatic switch arrangement whereby the circuit of said heating element is automatically closed and opened in order to maintain a substantially constant temperature of air flowing up through casing 1. While I prefer to have the casing of circular cross section, variations from a circular form may be made, as, for instance, the form may be elliptical, or any other geometric form, which will restrict the passage of air and at the same time eliminate the danger of the wet film contacting with the walls of the casing.

Various changes in the materials of construction, the form of the various elements, and the arrangement thereof may be readily devised. These and other changes may be made in the details of construction of my device, and the invention is not to be limited except by the character of the claim appended hereto.

What I claim is:

A film drier comprising a vertical elongated casing open at its lower end approximately circular in cross section, means for introducing a flow of air into said end, an opening at the upper end of said casing, a stationary holder for film at said upper end whereby said film is caused to hang in said casing, said holder having means for gripping both ends of a strip of film, a weight inserted in the loop at the lower end of said film, the diameter of said casing being slightly larger than the width of said film to provide a restricted cross section of casing for minimizing the amount of air flowing therethrough and to prevent the face of said film from touching the wall of said casing.

RUDOLPH SIMMON.
